Patented Nov. 17, 1914.

UNITED STATES PATENT OFFICE.

GUSTAVE J. WAGNER AND MYRON H. HOPKINS, OF GRAND RAPIDS, MICHIGAN, AS
SIGNERS TO THE O. & W. THUM COMPANY, OF GRAND RAPIDS, MICHIGAN.

STICKY-FLY-PAPER DEVICE.

1,117,284.

Specification of Letters Patent. Patented Nov. 17, 1914

Application filed September 12, 1913. Serial No. 789,555

To all whom it may concern:

Be it known that we, GUSTAVE J. WAGNER and MYRON H. HOPKINS, citizens of the United States, residing at Grand Rapids, Michigan, have invented certain new and useful Improvements in Sticky-Fly-Paper Devices, of which the following is a specification.

This invention relates to improvements in sticky fly paper devices.

The objects of this invention are: First, to provide a ribbon of sticky fly paper in roll form in a compact and effectively sealed package. Second, to provide a roll of sticky fly paper ribbon incased in such a manner that the ribbon can be readily drawn out. Third, to provide a package of this character which is effectively sealed with one edge of the ribbon properly protruding to facilitate its withdrawal from the case. Fourth, to provide an improved construction of pivot bearing in such a case.

Further objects, and objects relating to details and economies of construction and operation will definitely appear from the detailed description to follow.

We accomplish the objects of our invention by the devices and means described in the following specification.

The invention is clearly defined and pointed out in the claims.

A structure, which is a preferred embodiment of our invention, is fully illustrated in the accompanying drawing, forming a part of this specification, in which:

Figure I is a detail elevation view of a package of sticky fly paper ribbon embodying the principles of our invention. Fig. II is a similar view of the same with the protruding flap of the ribbon turned back disclosing the sealing means. Fig. III is a view of the sticky fly paper ribbon in use, the same being pulled out of the cylindrical box and suspended upon the hook, as illustrated. Fig. IV is an enlarged detail transverse sectional view on line 4—4 of Fig. I. Fig. V is a detail enlarged sectional view of part of the empty shell of the package showing details of the pivot bearing for the roller. Fig. VI is a detail sectional view on line 6—6 of Fig. III, showing the method of suspending the sticky fly paper ribbon when in use.

In the drawing, the sectional views are taken looking in the direction of the little

arrows at the ends of the section lines, and similar numerals of reference refer to similar parts throughout the several views.

Considering the numbered parts of the drawing, we provide a cylindrical shell 1, preferably made of paper, as paste board, with caps 2, 2 for its opposite ends, which body and cap contain a longitudinal slot 5 which does not completely intersect the wall, for the withdrawal of the ribbon. A little slack should be left at each end of the slot to afford a fibrous paper foundation for the sealing material. The caps 2 are of metal and are seamed onto the cylindrical shell at 3. A circular central indentation 4 is in each cap and affords a very smooth bearing for the roll 12 which is pitted to conform thereto. A ribbon of paper 6 of a width substantially the length of the slot 5 in the side of the box, coated with sticky material 7, 7 on its opposite surfaces and having an uncoated projecting end 8 perforated at 9 is wound into a roll upon the central cylindrical block 12. The inner end 6' of the ribbon 6 is folded back upon itself so that the cylindrical core 12 is held in a loop at the end of the ribbon. The slot 5 through which the ribbon is drawn is considerably wider than the thickness of the ribbon and its coating, and into the space by the side of the uncoated end of the ribbon we insert a length of soft string 13, such as a piece of candle-wicking, with a protruding end 13' folded back upon itself at a convenient point to be grasped to withdraw the same from the aperture and we seal the space with melted paraffin or similar wax 14. This retains the sticky contents within the package and prevents any leakage of the same. By this means we are able to produce a very satisfactory and effective clean package, from which the sticky material does not exude, and after the package is opened, it is only necessary to gently pull the ribbon 6 out when the sticky coating on both sides is exposed for use.

We provide, preferably, a small screw hook 16 for screwing into the wall, ceiling, window casing or frame 11 to hang up the ribbon. This hook is very small and may be readily wrapped with the main package so that the whole thing can be produced and sold for a small price. This overcomes some of the objections to the sticky fly paper in sheet form, as it provides the material in

a very compact package and requires no special attention further than to store the same in a cool place until it is desired for use. There is, of course, only a limited 5 sticky surface exposed by each of these devices. This, however, is found to be quite sufficient when the device is well placed to catch the small number of flies that manage to get into screened apartments.

10 We are aware, in this behalf, that sticky fly paper ribbon devices have been heretofore produced, but we are simply claiming improvements which result in economy of manufacture in an effective device for the 15 purpose which is easy to manipulate and make use of, and which is a very neat package when completed ready for distribution.

We desire to claim the novel features broadly and also the specific devices as 20 pointed out in the appended claims.

Having thus described our invention, what we claim as new and desire to secure by Letters Patent is:

1. In a suitable fly paper ribbon device, 25 the combination of a suitable cylindrical shell of paper with a longitudinal slot at one side intermediate the edges thereof; metal caps at the ends secured by seaming and having central bearings formed by indentation of the metal; a cylindrical core block disposed within the shell and conformed to be supported by said bearing; a ribbon of sticky fly paper wound into a roll about said block with a protruding 30 outer end; and a plug of string sealed with paraffin wax for the slot in proximity to the protruding end of said ribbon, as specified.

2. In a suitable fly paper ribbon device, 35 the combination of a suitable cylindrical shell of paper with a longitudinal slot at 40

one side intermediate the edges thereof; caps at the ends; a cylindrical core block disposed within the shell; a ribbon of sticky fly paper wound into a roll about said block with a protruding outer end; and a plug 45 of string sealed with paraffin wax for the slot in proximity to the protruding end of said ribbon, as specified.

3. In a suitable fly paper ribbon device, 50 the combination of a suitable cylindrical shell of paper with a longitudinal slot at one side intermediate the edges thereof; caps at the ends; a cylindrical core block disposed within the shell; a ribbon of sticky fly paper wound into a roll about said block 55 with a protruding outer end; and a plug sealed with wax for the slot in proximity to the protruding end of said ribbon, as specified.

4. In a suitable fly paper ribbon device, 60 the combination of a suitable cylindrical shell of paper with a longitudinal slot at one side; metal caps at the ends secured by seaming and having central bearings formed by indentation of the metal; a cylindrical 65 core block disposed within the shell and conformed to be supported by said bearing; a ribbon of sticky fly paper wound into a roll about said block with a protruding outer end; and a plug sealed with wax for 70 the slot in proximity to the protruding end of said ribbon, as specified.

In witness whereof, we have hereunto set our hands and seals in the presence of two witnesses.

GUSTAVE J. WAGNER. [L.S.]
MYRON H. HOPKINS. [L.S.]
